E. STIMSON.

Broadcast-Seeder

No. 14,837.

Patented May 6, 1856.

Fig. 2.

UNITED STATES PATENT OFFICE.

ENOS STIMSON, OF NORTH CRAFTSBURY, VERMONT.

IMPROVEMENT IN MACHINES FOR SOWING SEED BROADCAST.

Specification forming part of Letters Patent No. 14,837, dated May 6, 1856.

To all whom it may concern:

Be it known that I, ENOS STIMSON, of North Craftsbury, in the county of Orleans and State of Vermont, have invented a new and Improved Machine for Sowing Seed Broadcast; and I do hereby declare that the following is a full, clear, and exact description of the same, reference being had to the annexed drawings, making a part of this specification, in which—

Figure 1 is a longitudinal vertical section of my improvement. Fig. 2 is a horizontal section of same, looking upward, *xx*, Fig. 1, showing the plane of section.

Similar letters of reference indicate corresponding parts in the two figures.

My invention consists in a horizontal rotating tube placed underneath the hopper and communicating with it, the tube having a valve at each end, the valve being operated by means of an adjustable cam, as will be presently shown, so that the grain will be sown broadcast and behind the machine.

To enable those skilled in the art to make and use my invention, I will proceed to describe it.

A represents the hopper, which is supported by two uprights, *a a*, attached to the frame *B* of the machine. The frame *B* is supported by wheels *C C*.

D represents a vertical shaft, which passes through the center of the hopper *A*. The lower end of this shaft is stepped in, at *b*, on the frame *B*, as shown in Fig. 1, and the upper end of the shaft works in a cross-piece, *c*, on the upper part of the hopper.

The lower end of the shaft *D* has a bevel-wheel upon it, and also a hollow arm or tube, *F*, the shaft passing through the center of the arm or tube. The arm or tube is placed above the wheel *E*, and a tube, *d*, passes from the center of the hopper and within a flange, *e*, at the center of the arm or tube. Thus it will be seen that the grain will pass from the hopper *A* through the tube *d* into the hollow arm or tube *F*.

To the inner side of one of the wheels *C* there is attached a toothed wheel, *G*, into which a pinion, *H*, gears. This pinion is attached to one end of a shaft, *I*, which has a bevel-pinion, *J*, on its opposite end, the pinion *J* gearing into the bevel-wheel *E* on the shaft *D*. The outer bearing of the shaft *I* is in a lever, *K*, attached to one of the uprights *a*, which support the hopper.

To each end of the hollow arm or tube *F* there is pivoted a valve, *L*, as shown clearly in Fig. 2. These valves are kept closed by spiral springs *e'*, which are placed around rods *f*, attached to the back ends of the valves, the rods *f* being connected by pivots to rods *g*, which are pivoted to the arm or tube *F*. The inner ends of the rods *f* have friction-rollers *h* attached to them.

To the under side of the hopper *A* there is pivoted a board or plate, *M*. The inner edge of this board or plate has a semicircular recess, *i*, made in it. The board or plate *M* has a lever, *N*, attached to one end.

The operation is as follows: As the machine is drawn along the hollow arm or tube *F* will be rotated by means of the gearing previously described, and the grain in the hopper *A* will pass down through the tube *d* into the hollow arm or tube *F*, and will be thrown by centrifugal force out of the ends of the arm or tube *F*. The valves *L* are kept closed by the springs *e'* while the ends of the arm or tube are passing around one half of its revolution at the front of the machine; but as they perform the other half-revolution the friction-rollers *h* pass into the recess *i* in the board or plate *M*, which recess acts like a cam, or, in fact, is a stationary cam, and the valves are thereby opened, and the seed or grain will be thrown out from the arm or tube and sown broadcast behind the machine.

The quantity of seed or grain to be sown on a given area of ground is regulated by adjusting the board or plate *M* so that the valve *L* may be opened more or less as they pass around at the back of the machine.

Having thus described my invention, what I claim as new, and desire to secure by Letters Patent, is—

The rotating horizontal arm or tube *F*, provided with valves *L* at its ends and used in connection with the adjustable board or plate *M*, provided with the semicircular recess *i*, the above parts being constructed, arranged, and operating substantially as shown, for the purpose specified.

ENOS STIMSON.
